ROLLER REMOVING TOOL

Abram Glover, Rifle, Colo.

Application January 26, 1949, Serial No. 72,930

2 Claims. (Cl. 29—253)

1

This invention relates to a unique tool of extremely simple construction for use particularly by watchmakers in the moving rollers from the staffs of balance wheels and which operation is otherwise quite difficult to accomplish without injuring or damaging the staff or balance wheel due to the relatively small size of the parts and the tendency of rollers, which have not been removed for a considerable period of time, to stick or frictionally engage the staffs.

Still a further object of the invention is to provide a tool for the aforescribed purpose of extremely simple construction which constitutes a unitary structure and which may be efficiently employed for removing rollers from balance staffs without subjecting the staff to an impact blow.

Still a further object of the invention is to provide a tool which may be economically manufactured and sold and which will be efficient and durable for accomplishing its intended purpose.

Various other objects and advantages of the invention will hereinafter become more fully apparent from the following description of the drawing, illustrating a presently preferred embodiment thereof, and wherein:

Figure 1 is a top plan view showing the tool in an operative position;

Figure 2 is a longitudinal sectional view thereof, on a slightly enlarged scale, taken substantially along a plane as indicated by the line 2—2 of Figure 1 and with the balance wheel removed from the tool, and

Figures 3 and 4 are enlarged cross sectional views taken substantially along planes as indicated by the lines 3—3 and 4—4, respectively, of Figure 1.

Referring more specifically to the drawing, the roller removing tool in its entirety and which comprises the invention is designated generally 5 and includes a head 6 formed of spaced substantially parallel plates 7 and 8 of substantially uniform size and shape, the upper plate 7 of which is broken away in Figure 1 to illustrate internal details of the tool 5, as will hereinafter become apparent.

The tool 5 also includes a pair of elongated levers 9 and 10 which are tapered in width substantially from end-to-end thereof and the enlarged ends of which are disposed between the plates 7 and 8 forming the head 6. The enlarged end of the lever 9 is rigidly secured in the head 6 by a plurality of rivets or other fastenings 11 which extend therethrough and through the plates 7 and 8 and by which said plates are connected to form the head 6. The enlarged end

2

of the other lever 10 is disposed in the head 6 and swingably connected thereto by a single rivet or pivot pin 12 which extends loosely therethrough and through the plates 7 and 8 so that the lever 10 may swing toward and away from the lever 9 in a plane corresponding to the plane of said levers.

A spring 13 comprising a resilient strand of relatively heavy gauge wire the resiliency of which causes said strand to normally assume a straight position, has one end thereof slidably secured in the head 6 between a screw 14 which extends detachably and threadedly through portions of the plates 7 and 8; and a screw 15 which is disposed substantially parallel to said end of the spring 13 and which is disposed between said plates 7 and 8 and a portion of the enlarged end of the lever 9 and said end of the spring 13. The portions of the plates 7 and 8 and lever 9 which are engaged by the screw 15 may be threaded for detachably mounting said screw therein, and sufficient space is afforded between the screws 14 and 15 to enable aforementioned end of the spring 13 to slide relatively thereto, for a purpose which will hereinafter become apparent. The spring 13 extends from the screws 14 and 15 through the head 6 in a direction transversely of the longitudinal axis of the tool 5 and is tensioned to curve around the arcuate, convex inner end 16 of the lever 10 and has its opposite end projecting from the head 6 along the outer longitudinal edge of the lever 10. Said last mentioned, exposed end of the spring 13 slidably engages in a loop 17 which is connected to the lever 10, adjacent the head 6 and which projects laterally from the outer longitudinal edge thereof. The tendency of the spring 13 to assume a straight position will cause the last mentioned end thereof to exert a pull on the link 17 to cause the lever 10 to swing on its pivot 12 and relatively to the head 6 in a direction away from the lever 9 and so that said levers 9 and 10 will be normally disposed in outwardly diverging relationship from the head 6 rather than in nearly parallel relationship, as seen in Figure 1. The rounded inner end 16 of the lever 10 is eccentric with respect to the pivot 12 so that a portion thereof will engage the adjacent edge of the enlarged inner end of the lever 9 for limiting the swinging movement of the lever 10 away from the lever 9 under the biasing action of the spring 13.

The upper surfaces of the levers 9 and 10 from a line disposed in transverse alignment with the inner end of the head 6, are beveled on their upper sides from adjacent their outer or remote

longitudinal edges to their inner, adjacent longitudinal edges as clearly illustrated in Figures 3 and 4 at 18 and 19, respectively. Said beveled upper surfaces 18 and 19 of the levers 9 and 10 provide substantially sharpened or feathered inner edges 20 and 21 of the levers 9 and 10, respectively, adjacent the head 6. The bevel of the upper surfaces 18 and 19 diminishes from the head toward the outer ends of said levers and ceases at points spaced from said outer ends and accordingly the thickness of the inner, tapered edges 20 and 21 increases in a direction away from the head 6. As clearly illustrated in Figures 3 and 4, the opposite, bottom sides of the levers 9 and 10 are substantially flat and disposed in the same plane.

To utilize the tool 5 for removing a roller 22 from the staff 23 of a balance wheel 24, said tool is initially inverted from its position of Figure 1 so that the beveled surfaces 18 and 19 will be facing downwardly. The staff 23 and roller 22 are then inserted downwardly through the space between the lever edges 20 and 21 and so that the balance wheel 24 will rest on the flat, normally bottom surfaces of the levers 9 and 10 and so that the roller table 25 will bear against portions of the beveled surfaces 18 and 19. The balance wheel 24 and attached parts are then moved to a position adjacent the head 6 after which the tool is inverted so that the beveled surfaces 18 and 19 will be uppermost. With one hand grasping the tool adjacent the free end of the levers 9 and 10, the index finger of the other hand is positioned under the balance wheel and the thumb over the roller table to guard against loss of the roller when removed. The wheel and roller are then moved away from the head 6 until the edges 20 and 21 bind between the roller table and the arm of the balance wheel, if necessary the levers 9 and 10 being moved slightly toward one another to prevent the roller table from moving out of engagement with the beveled surfaces 18 and 19. With the balance wheel and roller table thus positioned, pressure is exerted against the free ends of the levers 9 and 10 for swinging the lever 19 toward the lever 9 to cause the roller table 25 to ride laterally upwardly on the beveled surfaces 18 and 19 which thus function as cams for forcing the roller and roller table away from the balance wheel. If this is insufficient to loosen the roller so that it can be readily removed with the fingers from the staff 23, pressure on the levers 9 and 10 are released and the balance wheel and roller are moved still further toward the free ends of the levers and the operation, previously described, repeated. The tool 5 may also be utilized with balance wheel units having two piece rollers by repeating the operation previously described to press the larger of the two rollers against the smaller roller of the two piece, double roller. The inner edge of the plate 8 has a recess 26 to accommodate the balance wheel 24 when disposed near the head 6.

Various modifications and changes are contemplated and may obviously be resorted to, without departing from the spirit or scope of the

invention as hereinafter defined by the appended claims.

I claim as my invention:

1. A roller removing tool comprising a head, a lever fixedly secured at one end thereof to the head and projecting therefrom, a second, movable lever having one end pivotally connected to the head and extending therefrom, said movable lever being mounted to swing in a plane corresponding to the plane of each of said levers, spring means for yieldably urging the free end of the movable lever away from the fixed lever, said levers having complimentary sides beveled from the outer edges to the inner edges of the levers adjacent the head and defining complimentary beveled surfaces, the slope of said beveled surfaces diminishing toward the free ends of the levers, said beveled surfaces providing relatively thin adjacent lever edges near the head which increase in thickness in direction away from the head, said levers being adapted to have a balance wheel staff and roller extending between their adjacent edges and with a balance wheel of the staff bearing against the opposite sides of the levers and the table of the roller bearing against the beveled surfaces thereof, said balance wheel and roller being movable longitudinally of the levers for wedging the adjacent lever edges between the balance wheel and roller table, and said movable lever being swingable toward the stationary lever to cause the roller table to ride outwardly on said beveled surfaces for displacing it on the staff away from the balance wheel.
2. A balance wheel roller removing tool comprising a head, a pair of levers connected to and projecting from said head in the same direction, one of said levers being rigidly secured to the head and the other of said levers being pivotally connected thereto for swinging movement toward and away from the rigid lever in a plane corresponding to the planes of the levers, said levers having outer longitudinal edges of uniform thickness from end-to-end thereof, the portions of said levers adjacent the head being beveled on corresponding sides thereof from their outer to their inner longitudinal edges to provide complimentary thin inner, adjacent edges near the head, and the slope of said beveled sides diminishing from the head toward the free ends of the levers whereby the thickness of the inner edges of said levers is increased in a direction away from the head.
